(Cl. D92—1)

To all whom it may concern:

Be it known that I, Gino Scalambardé, a citizen of the United States of America, residing in Jamaica, county of Queens, and State of New York, have invented a new, original, and ornamental Design for a Textile Fabric or Similar Article, of which the following is a specification, reference being had to the accompanying drawing, forming part thereof, wherein,

The figure on the drawing is a plan view of a piece of textile fabric showing my new design.

The design unit is outlined by dotted lines, and is repeated as indicated.

I claim:

The ornamental design for a textile fabric or similar article, substantially as shown and described.

GINO SCALAMANDRÉ.
